Kilton Lenoir

UNITED STATES PATENT OFFICE.

WILLIAM S. WITTEN, OF CHICAGO, ILLINOIS.

LOCK.

Application filed November 14, 1919. Serial No. 337,905.

To all whom it may concern:

Be it known that I, WILLIAM S. WITTEN, a citizen of the United States, and a resident of Chicago, in the county of Cook and State 5 of Illinois, have invented certain new and useful Improvements in Locks, of which the following is a specification, reference being had to the accompanying drawings.

My invention relates to latches or locks 10 and has for its object to provide an improved lock or latch suitable for use on automobile doors, freight car doors, gates, and similar devices, in which the use of springs will be avoided, and which will be simple 15 and substantial in construction so that it will not readily get out of order, and may be cheaply manufactured. I accomplish this object as illustrated in the accompanying drawings and as hereinafter described.

What I regard as new is set forth in the claims.

In the drawings in which I have illustrated several forms in which my invention may be embodied,—

Fig. 1 is a perspective view of part of the door of an automobile showing my improved lock in place thereon as viewed from the inner side of the door;

Fig. 2 is a perspective view of part of an automobile body showing that part of the door jamb which cooperates with the lock shown in Fig. 1;

Fig. 3 is a view illustrating the interior of my improved lock with the lock in operative position, being substantially a vertical section on line 3—3 of Fig. 4;

Fig. 4 is a vertical cross-section on line 4—4 of Fig. 3;

Fig. 5 is a perspective view of part of an automobile having my improved lock applied to the doors thereof;

Fig. 6 is a view similar to Fig. 3 showing my invention embodied in a gate latch and lock;

Fig. 7 is a vertical cross-section on line 7—7 of Fig. 6;

Fig. 8 is a detail, being a partial vertical section on line 8—8 of Fig. 6;

Fig. 9 is an elevation of part of a farm 50 gate having applied thereto the lock shown in Fig. 6;

Fig. 10 is a view showing the interior of a similar lock designed particularly for use on freight car doors, said view being sub-

stantially a vertical section on line 10—10 of Fig. 11;

Fig. 11 is a cross-section on line 11—11 of Fig. 10; and

Fig. 12 is an elevation, partly broken away, showing the application of the lock 60 shown in Fig. 10 to a freight car door.

Referring first to the arrangement shown in Figs. 1 to 5, it will be observed that my improved latch or lock comprises a casing 13, in the form of a narrow rectangular 65 box-like structure, in which is mounted a swinging latch composed of a shank 14 having at one end a cross-head 15, the lower end portion 16 of which forms a latch member, and the upper end portion 17 of which 70 not only adds weight to said cross-head but also aids in resisting twisting strains sustained by the latch member 16, since by this construction the cross-head has an extended bearing on the side walls of the casing. The 75 shank 14 is mounted in a substantially horizontal position and is adapted to swing up and down about a pivot 18 fitted in a bearing 19 near the end of the shank 14 opposite that which carries the cross-head 15, said 80 bearing being preferably offset, as shown in Fig. 3. By thus mounting the latch is is adapted to swing in a vertical plane so that the cross-head moves substantially vertically to project or retract the latch member 16 85 thereof through a slot 20 provided in the lower margin of the casing 13. Preferably this opening or slot is adjacent to one end of the casing, as shown in Fig. 3, so that when the casing is applied to a door, such 90

as an automobile door 21, the latch member 16 will be adjacent to the outer edge of said door, as shown in Fig. 1. 22 indicates a stop secured in the casing 13 under the shank 14 to limit the downward movement thereof, 95 as shown in Fig. 3. It will be apparent that the latch will normally occupy the position shown in Fig. 3 under the action of gravity, and that by rocking said latch in a clockwise direction as viewed in Fig. 3, the latch 100 member 16 may be withdrawn into the casing. In the construction shown in Figs. 1 to 5, the latch is rocked to move the latch member 16 out of operative position by means of handles or levers 23 at opposite 105 sides of the door 21 and secured to the pivot 18, which is journaled in the sides of the casing and is non-rotatably secured to the

shank 14 so that said shank may be swung upward by rocking said pivot. The levers 23 are illustrated as normally occupying an inclined position, but of course they may be 5 otherwise arranged if desired.

In order that the latch may be locked in its operative position the shank 14 is provided at or near its pivoted end with a lug 24 which is adapted to be engaged by a bolt 10 25, indicated by dotted lines in Fig. 3, the arrangement being such that by projecting said bolt into the path of the lug 24 the rocking of the latch may be prevented. The bolt 25 may be projected or retracted in 15 any suitable way, as by a key inserted through a keyhole 26.

When the door 21 is shut the latch member 16 is adapted to engage a bevelled lug or keeper 27 which projects up into a 20 groove 28 provided in the door jamb 29 of the automobile body 30, as shown in Fig. 2, said groove being adapted to receive the outer end of the casing 13 in the usual way. As shown in Fig. 4, the side margins of the 25 latch member 16 are bevelled so that when the door is being closed the said latch member rides up easily on the outer bevelled face of the lug 27 and when the door has been completely closed said latch member 30 drops down along the inner bevelled margin of said lug, as shown in Fig. 4. By this construction the latch has a wedging action which gives it a tendency to work down more snugly in operative relation to 35 the lug 27 under the influence of the weight of the cross-head so that the door is held tightly in closed position and is not apt to rattle. If desired, the latch member 16 may be forced down manually by operating 40 either of the levers 23, thereby locking it still tighter in operative position. When the door is open the latch may be freely 45 swung upward by pressure applied to the latch member 16 so that the door latches easily, and the latch does not have the tendency to stick which is an objectionable feature of many spring operated latches.

In Figs. 6 to 9 I have shown the same principle applied to a gate latch or lock 50 with the added feature that the latch is reversible so that the latch member may be placed at either end of the casing. Also the shank of the latch extends out beyond the casing to provide a handle by which 55 the latch may be operated to unlock the gate. Referring to said figures,—31 indicates the lock casing which is provided with slots 32, 33 at its opposite lower corners. 34 indicates the shank of the latch 60 which is intermediately mounted upon a pivot 35 located centrally between the ends of the casing, as shown in Fig. 6, and is provided at one end with a cross-head 36 forming a latch member 37 and a weighted head 38. The latch member 37 extends

through one of the slots 32 or 33, while the opposite end of the shank 34 extends through the opposite slot, as illustrated in said figure. The shank 34 is also provided with a lug 38 at one side of its pivot 70 corresponding with the lug 24 hereinbefore described. The latch member 37 is adapted to engage a keeper 39 secured to one of the fence posts 40, as shown in Figs. 8 and 9, said keeper having an inclined guide 41, as shown in Fig. 8. In this case, also, the latch member 37 is bevelled so as to secure the wedging action hereinbefore described. The casing 31 is provided with a locking bolt 42 adapted to engage the lug 38, as indicated by dotted lines in Fig. 6, said bolt being preferably mounted in a supplemental casing 43 and being arranged to be actuated by a key inserted through a keyhole 44. In Fig. 6 two positions of the supplemental casing 43 are indicated, one being in full lines and the other being in dotted lines. The position shown in full lines is that which the locking bolt occupies when the latch is arranged as shown in said figure, but 90 it will be apparent that if desired the latch may be turned end for end so that the cross-head 36 thereof would be at the right hand end of the casing as viewed in Fig. 6 instead of at the left hand end thereof. In 95 that case the supplemental casing 43 would be shifted to the position shown in dotted lines and secured thereby by means of the screw holes provided for that purpose, as indicated. Downward movement of the 100 latch member is limited by a pin 45 shown in Fig. 6, and in case of reversal of the latch as above suggested this pin would be shifted to a pin-hole 46 provided to receive it. In this construction the latch is moved 105 to its operative position by gravity and is moved out of operative position by means of the end of the shank 34 which projects out of the casing, as shown in Figs. 6 and 9. In other respects the latch operates in 110 the manner already described.

In Figs. 10 to 12 my improved lock is shown applied to a freight car door which may be either of the type which moves endwise only or that in which the door swings outwardly as well as moves endwise. In the construction shown in said figures,—47 indicates the casing of the lock, 48 the shank of the latch, 49 the cross-head, and 50 the latch member. The latch is mounted upon a pivot 51 in the manner previously described and its shank 48 extends out of the casing to provide a handle so that it may be rocked conveniently. The casing is adapted to be secured to the outer surface of 125 the door 52 near its lower margin, one of the locks being provided at each of the two lower corners of the door, as shown in Fig. 12. Adjacent to the lower margins of the door are secured keepers 53 in position to be 130

engaged by the latch members 50, said keepers having bevelled surfaces adapted to cooperate with the bevelled portions of the latch members 50, as shown at 54 in Fig. 11, 5 thus securing the wedging action hereinbefore described. By this means the lower margin of the door may be bound tightly against the side of the door sill 55, as shown in Fig. 11.

10 For locking the latch either in operative or in inoperative position the handle portion of the shank 48 is provided with a lug 56 adjacent to its pivot, as shown in Fig. 10, and said lug is adapted to be engaged by a 15 swinging cam 57 mounted upon a pivot 58 and having an arm 59 which extends out of the casing, as shown in said figure. When the cam 57 is in the position shown in full lines in Fig. 10, which position it normally 20 assumes by gravity, a shoulder 60 provided on said cam engages the end wall of the casing 47, thereby preventing the cam from swinging further to the right as viewed in said figure. This locks the latch in its operative position, as it cannot be rocked clockwise as viewed in said figure, to move it out of its operative position, because of the engagement of the lug 56 with said cam. When the latch is in its operative position, 25 however, the cam may be moved to the position shown in dotted lines by inward pressure on the arm 59 so as to carry the lower portion of the cam far enough to the left to permit the lug 56 to pass it when the latch 30 is moved out of operative position. When the latch is in its inoperative position, shown in dotted lines in Fig. 10, it is automatically locked in that position because counterclockwise movement of the latch 35 tends to swing the cam to the left, which movement is prevented when said cam is in its dotted line position by the engagement of the outer end of the arm 59 with the end wall in the casing 47. The latch may, however, be released by restoring the cam to its 40 full line position, either by hand, or by rocking the latch a little further in a clockwise direction and thereby permitting the lug to return to its normal position by gravity.

50 In all the several forms of locks shown and described, the latch member normally assumes its operative position under the action of gravity, although when the door or gate is open the latch responds readily to upward pressure so that it is easily moved into operative relation to its keeper. After engaging the keeper, however, the wedging action of said members on each other holds the door or gate firmly in position and any tendency to vibrate the door or gate only serves to wedge said members more tightly together, so that the door or gate does not rattle and cannot be accidentally unlatched.

It will be obvious that my improved latch

may be used in a great variety of situations 65 besides those described, and the claims hereinafter made are, therefore, to be construed accordingly.

What I claim as my invention and desire to secure by Letters Patent, is—

1. A lock comprising a shank pivoted to swing up and down about a horizontal axis and having a downwardly projecting latch member at one end portion thereof, and an upwardly extending head adjacent to said 75 latch member.

2. A lock comprising a shank pivoted to swing up and down about a horizontal axis and having a downwardly projecting latch member at one end portion thereof, an upwardly extending head adjacent to said 80 latch member, and means for locking said latch member in operative position.

3. A lock comprising a shank pivoted to swing up and down about a horizontal axis 85 and having a cross-head at one end portion thereof, the lower portion of said cross-head constituting a latch member.

4. A lock comprising a shank pivoted to swing up and down about a horizontal axis 90 and having a downwardly projecting latch member at one end portion thereof, an upwardly extending head adjacent to said latch member, and means whereby said shank may be rocked to move said latch 95 member out of operative position.

5. A lock comprising a shank pivoted to swing up and down about a horizontal axis and having a cross-head at one end portion 100 thereof, the lower portion of said cross-head constituting a latch member, and means whereby said shank may be rocked to move said latch member out of operative position.

6. A lock comprising a shank pivoted to swing up and down about a horizontal axis 105 and having a downwardly projecting latch member at one end portion thereof, and an upwardly extending head adjacent to said latch member, in combination with a keeper adapted to cooperate with said latch member 110 and having wedging engagement therewith.

7. A lock comprising a casing, a shank pivoted in said casing to swing up and down about a substantially horizontal axis 115 and having a downwardly projecting latch member at one end portion thereof adapted to project through said casing, and an upwardly extending head adjacent to said latch member.

8. A lock comprising a casing, a shank pivoted in said casing to swing up and down about a substantially horizontal axis and having a downwardly projecting latch member at one end portion thereof adapted to 125 project through said casing, an upwardly extending head adjacent to said latch member, and a member outside of said casing for

rocking said shank to move said latch member out of operative position.

9. A reversible lock comprising a casing, a reversible shank pivotally mounted therein between its ends and having a laterally projecting latch member at one end portion thereof, and slots in said casing for the passage of said latch member, said slots being equidistant from the pivot of said shank.

10. 10. A reversible lock comprising a casing, a reversible shank pivotally mounted therein between its ends and having a laterally projecting latch member at one end portion thereof, slots in said casing for the passage of said latch member, said slots being equidistant from the pivot of said shank, a lug carried by said shank at one side of the pivot thereof, and means cooperating with said lug for locking said latch member in operative position.

11. A reversible lock comprising a casing, a reversible shank pivotally mounted therein between its ends and having a laterally projecting latch member at one end portion thereof, the opposite end portion of said shank extending out of said casing, and slots in said casing for the passage of said latch member, said slots being equidistant from the pivot of said shank.

30. 12. A lock comprising a casing, a shank pivotally mounted therein to swing in a vertical plane, and a downwardly project-

ing latch member carried by said shank at one side of the pivot thereof and movable down through the lower marginal portion 35 of the casing in a line substantially perpendicular thereto.

13. A lock comprising a shank pivoted to swing up and down about a horizontal axis and having a downwardly projecting latch 40 member at one end portion thereof, and means adapted to engage said shank and operating to lock said latch member either in operative or in inoperative position.

14. A lock comprising a casing, a shank 45 pivotally mounted therein to swing in a vertical plane, and a downwardly projecting latch member carried by said shank at one side of the pivot thereof and movable down through the lower marginal portion 50 of the casing in a line substantially perpendicular thereto, said shank being arranged to be reversed to change the position of said latch member with relation to the casing.

15. A reversible lock comprising a casing, 55 a shank pivotally mounted therein to swing up and down and having a projecting latch member extending downwardly beyond the casing, said latch member being arranged to be reversed, and locking means mounted in 60 said casing and adapted to lock said latch member when arranged in either of its positions.

WILLIAM S. WITTEN.
